J. J. MORROW

AUTOMATIC ROLLER FASTENER

Filed Feb. 16, 1926

FIG. 2.

FIG. 3.

FIG. 1.

INVENTOR
JOHN J. MORROW
BY
Greenbow & Reges
ATTORNEYS

UNITED STATES PATENT OFFICE.

JOHN J. MORROW, OF NEW YORK, N. Y., ASSIGNOR TO A. C. WICKE MANUFACTURING COMPANY, OF NEW YORK, N. Y., A CORPORATION OF NEW YORK.

AUTOMATIC ROLLER FASTENER.

Application filed February 16, 1926. Serial No. 38,518.

This invention relates to door fasteners and more particularly to those adapted for use on refrigerator doors.

5 An object of the present invention is to provide a door fastener of simple and compact construction and of neat appearance.

Another object of the invention is to provide a door fastener of a practical and sanitary character which may be produced at 10 a minimum cost.

Another object of the invention is to provide a door fastener having a housing for enclosing means for automatically oscillating the latch.

15 A further object of the invention is to provide a door fastener having a housing which supports the latch and also encloses the mechanism for automatically operating the latch.

20 A further object of the invention is to provide a door fastener with means for automatically operating the latch and also means for locking the latch against movement.

25 Other objects and advantages of the invention will be evident as the following description is read.

In the manufacture of sanitary equipment such as refrigerators and particularly those 30 of the relatively small type commonly termed ice boxes, it is important that the doors be held in firm contact with their seat. Door fasteners for this purpose have been employed, as for example that shown in my Patent No. 1,529,858 in which an arm 35 engages a keeper with a cam surface to force the door firmly against its seat. In this type of fastener, however, means are provided for operating the latch from both 40 sides of the door, whereas, since the present fastener is mostly used for small refrigerators, the inside operation of the latch is not essential.

The small type of fastener must, however, 45 present a neat appearance and be of such construction as to be practical from a manufacturing cost standpoint.

50 It is also desirable in door fasteners of the present type to provide one which may be readily secured to the face of the door without mutilating the latter. This is of especial importance since in refrigerators of the household type the wooden frame and cover is made relatively thin in order to

provide a relatively light weight box as well as one neat in appearance.

55 In addition it is preferred to mount the operating mechanism in such manner that it will not accumulate dust and grease and in which the spring is of the compressive type eliminating the danger of the automatic operation of the latch becoming ineffective through breakage as is the case with springs of the torsional type.

In addition to providing the foregoing 60 advantageous features, the present invention provides a fastener wherein a combined housing and bearing bracket is employed and also means whereby the latch may be conveniently and effectively locked against 65 movement.

70 The invention will be more fully understood by reference to the accompanying drawing in which:

Fig. 1 is a front view of my fastener engaged with the keeper of a door.

75 Fig. 2 is a vertical sectional view of the fastener taken on line II—II in Fig. 1 and

Fig. 3 is a fragmentary sectional view of the fastener taken on line III—III in Fig. 2.

In the embodiment of the invention illustrated in the drawing, the latching-device or fastener comprises a casing or housing 1, which may be suitably positioned on a door 2 and secured by bolts 3 passing through flanges 4 and 5. The housing may 80 be positioned adjacent to the edge of the door and is adapted to carry a latch mechanism for engagement with a keeper 6 secured to the jamb 7 of a door frame and in the proper operable position with relation to the latch.

85 As shown, the latch mechanism may comprise a hand lever 10 secured to a shaft 11 journaled in bearings 13 and 14 at opposite sides and preferably integral with the housing 1. The shaft 11 may extend from bearings 13 and 14 and have secured thereto a latch or locking-arm 15 having a roller 16 at the free end thereof to traverse a cam surface 17 on the keeper 6 and hold the 90 door against its seat when closed.

95 The locking arm is operated automatically to engage the keeper upon a closure of the door by reason of a helical compression spring 18 positioned in the housing 1. The spring is disposed on a projection 19 integral with an upper wall 21 of the housing and on

a projection 22 on an end of an operating lever 23 which may be integral with hub 24 of the hand lever 10. The helical spring 18 is so disposed as to normally force the operating lever downwardly thus causing a similar movement of the locking-arm 15 when the door is closed. The roller of the locking-arm traverses an inclined surface 26 of the keeper 6 and is raised in opposition to the spring 18 which subsequently acts to move the roller downwardly and engage with the cam surface 17 of the keeper and secure the door against its seat. The spring 18 is so arranged in the housing that its axial line or line of force under expansion will be most efficient to cause the oscillatory movement of the end of the operating lever 10. By reason of the properly directed action of the potential energy of the spring 18 when under compression, a smooth and effective automatic action of the latch is attained each time the door is closed.

In addition to securing a door, by the latch, it is desirable to provide means for locking the door to prevent unauthorized entrance to the refrigerator or compartment. The present invention, therefore, includes a fin or lug 27 integral with the underside of the operating lever 23. The lug is thus movable with the said lever and positioned to project through a slot 28 at the bottom 29 of the housing when the latch is in position to secure the door to the keeper.

The lug 27 is provided with a transverse aperture 29 through which an obstructing member may be inserted, as the bale 31 of a padlock 32 indicated in dotted lines in Fig. 2. When a padlock or the like is applied to the lug 27, while the latch is engaged with the keeper, it will be evident that the lug is prevented from returning to the housing and consequently no actuation of the latch can be effected.

The present invention provides a lockable latch with a minimum amount of movable parts of simple construction easily assembled and relatively low in production cost, thus making it possible to equip the smaller size refrigerators or ice-boxes with a latch comparable with that of the larger and more expensive type. Furthermore, the above advantages are attained in the present device by a novel construction in which the parts most subject to the collection of dust are enclosed in a housing which is utilized to pivotally support other members in such position as to be readily accessible for cleaning. It will be appreciated that by reason of the present invention a sanitary and practical device is provided.

Although a preferred embodiment of the invention is shown and described herein, it is to be understood that changes and modifications may be made therein without departing from the spirit or scope of the invention as set forth in the appended claim.

What is claimed is:

In combination with a keeper secured to a door jamb, a door fastener comprising a latch, said latch being pivotally mounted to engage said keeper by movement in a plane normal to the door, means for actuating said latch to engage the same with said keeper, a housing enclosing said actuating means, bearings upon said housing, a hand lever journaled in said bearings and associated with said latch, a locking lug upon said lever, an aperture in said casing to permit the projection of said locking lug when the latch is engaged with said keeper and means for securing said lug in its projected position to render the latch inoperative.

In testimony whereof I affix my signature.

JOHN J. MORROW.
